METHOD AND APPARATUS FOR FINISHING
HATSHerbert H. Watson, Jr., Norwalk, Conn., assignor
to Hat Corporation of America, Norwalk,
Conn., a corporation of Delaware

Application July 26, 1938, Serial No. 221,294

11 Claims. (Cl. 223—14)

The present invention relates to a process for forming a beaded edge on the brim of hats and to apparatus for accomplishing such process.

Heretofore the brims of hats have usually been provided with beaded edges for the purpose of improving their appearance and obtaining a so-called tied edge which strengthens the brim, retains the shape thereof and prevents the outer edge from unravelling. The usual practice for obtaining this effect was to fold back the outer marginal section of the brim and superpose the same upon the main section of the brim, and then either to felt the turned-back marginal section into the main brim section or to sew the two superposed sections together.

However, the process of felting together the superposed sections and making a so-called "felted edge" required very careful manual operations by highly skilled workers, and therefore could be applied only to high-priced hats. On the other hand, sewing the superposed sections together usually led to a less slightly appearance of the brim than hats with "felted edges," and the seam would sometimes become torn and unravelled. Therefore, hats with such sewed brims were not received by the trade with great favor.

It is the principal object of the present invention to provide a new process for forming a beaded edge on a hat brim, imparting thereto an improved appearance and constituting a so-called tied edge which retains the shape of the brim and prevents fraying or unravelling of the outer marginal portion thereof.

Another important object of the present invention is the provision of a hat brim with an outer marginal section of greater thickness and solidity than the main section thereof and which consists of a single layer of material as distinguished from a folded-over or double layer.

It is another object of the present invention to provide a process and an apparatus for producing a brim with a beaded and tied edge in a very inexpensive and simple manner and without requiring highly skilled workers.

It is a further object of the present invention to provide a process and an apparatus for forming such a beaded and tied edge by a continuous operation and uniform movement, and entirely mechanically.

Still another object of the invention resides in a process and apparatus for simultaneously finishing the brim of a hat and forming a bead thereon.

One of the disadvantages of the ironing methods known prior to the invention wherein a nonrotating iron is moved relative to a stationary hat brim, or a rotating hat brim is moved relative to a stationary iron, is that considerable friction is produced between the brim and the iron which results in a shiny appearance of the ironed portions of the brim.

It is a further broad object of the invention to iron a hat brim in such a manner as to reduce the friction between the iron and the brim as much as possible and thereby avoid a shiny appearance of the pressed portions.

An important feature of the invention for attaining the latter object resides in concurrently applying rolling pressure upon the hat brim by suitable rotatable means, and moving the hat brim and the means relative to each other and at the peripheral speed of the rotatable means.

Another feature of the invention consists in the provision of mechanism which is continuously and progressively movable relative to the hat and along the hat brim, and which works concurrently and automatically on the brim to confine and compress the outer section thereof within a groove whereby a uniform bead is formed of a strength depending on the pressure applied.

Another feature of the invention resides in a suitable apparatus for continuously rotating the hat and concurrently and automatically working upon an intermediate section of the brim so as to flow portions thereof gradually toward the outer margin and thereby increase the same in thickness and strength.

Another feature of the invention resides in the provision of a pair of rotating rollers at opposite sides of a hat brim and of a cross-sectional shape corresponding with the final desired shape of the hat brim, and including a peripheral groove in at least one of the rollers.

A further feature of the invention consists in operating the last-mentioned rollers relative to each other and relative to the brim of the hat in such a manner as to mold a beaded and tied edge on the brim.

It is another object of the present invention to soften the material of the hat brim and loosen the fibers thereof to facilitate the bead-forming operation.

A feature of the invention for attaining the latter object resides in the provision of one or more nozzles for continuously projecting a current of steam at least upon one side of the hat

brim as the hat is being rotated relative to the bead-forming rollers.

It is still another object of the invention to maintain the desired shape of the hat brim while a bead is formed along the outer edge thereof and to further shape the brim during such bead-forming operation.

A feature for attaining this object resides in the provision of mechanism for guiding the brim of the hat properly between the bead-forming rollers, maintaining the proper distance between the crown of the hat and the rollers, urging the rollers gradually toward each other so as to exert a rolling pressure upon the opposite sides 10 of the hat brim, and gradually extending said pressure from an intermediate section of the brim toward the outer edge thereof.

Other objects, features and advantages will become apparent from the following detail 20 description and the drawings, in which:

Figure 1 is a plan view of the novel bead-forming apparatus.

Fig. 2 is a sectional view taken along line 2—2 of Fig. 1.

Fig. 3 is a sectional view taken along line 3—3 of Fig. 1.

Fig. 4 is an enlarged sectional view showing the bead-forming elements of the novel apparatus in operative position with a portion of a 30 hat.

Fig. 5 is a detail side view of the guide block of the apparatus shown in Fig. 1.

Before describing the present improvements and mode of operation thereof in detail it should be understood that the invention is not limited 35 to the details of construction and arrangement of parts shown in the accompanying drawings, which are merely illustrative of the present preferred embodiments, and the phraseology employed is for the purpose of description and not of limitation.

Referring more particularly to the drawings, a driving shaft 10 which is rotatably guided within bearings 11 mounted on a base plate 12, is provided at one end with a pulley 13 which, in turn, may be driven by a motor (not shown) through a suitable driving belt. A worm 14 is secured to driving shaft 10 near the other end and engages a worm gear 15 on one end of a shaft 16 rotatably mounted with bearings 17 and 18 secured to the underside of the base plate 12. A roller 19 having a concave portion 20 forming a rotatable support for the brim 21 of a hat is secured to shaft 16 and projects through an aperture 22 in the base plate 12 to such an extent that the forward edge 23 of the concave portion 20 is at an even level with the upper surface of the base plate 12, as clearly shown in Fig. 2. A gear 24 on shaft 16 engages a similar gear 25 on an upper shaft 26 supported in bearings 27 and 28, for rotating the upper shaft 26 in a direction opposite to the rotation of the lower shaft and at the same speed. A roller 29 having a generally convex portion 30 constituting the bead-forming 60 and brim-finishing iron, is secured to the forward end of the upper shaft 26.

As shown particularly in Figs. 2 and 4, the convex portion 30 of roller 29 is provided at its rear end with a peripheral groove 31 which is designed to form and accommodate the bead 32 on the hat brim 21. Furthermore, the radius of curvature of the upper roller 29 is slightly smaller than that of the lower roller 19 so that the space 33 between the two rollers decreases gradually 70 from the forward edge of the rollers toward the

groove 31 in roller 29. Adjacent groove 31 roller 29 is provided with an enlarged hub 34 having within its rear face an annular chamber 35 for heating the roller 29, as will be later described. The lower roller 19, on the other hand, is provided 5 with a reduced cylindrical portion 36 which also forms a heating chamber 37 at the free end thereof. The wall 38 intermediate the portions 29 and 36 of the lower roller 19 is designed to slide along the corresponding wall 39 of the upper 10 roller 29 and substantially in engagement therewith so as to limit movement of upper roller 29 toward the left as seen in Fig. 2.

As shown particularly in Fig. 3, bearing 28 supporting the upper shaft 26 consists of a lower 15 block 40 in which are mounted a pair of bolts 41. An upper bearing block 42 is slidably mounted on bolts 41 so as to be movable in a vertical direction relative to the lower block 40. Coil springs 43, the tension of which is adjustable by nuts 44, act 20 upon the upper bearing block 42 to depress the same and normally maintain the upper shaft 26 in predetermined position relative to lower shaft 16 and to maintain gears 24 and 25 in engagement with each other. A pair of bolts 45 act to 25 secure bearing 17 of the lower shaft 16 and bearing block 40 to base plate 12.

A bar 46 connected at one end by means of a chain 47 to a foot pedal (not shown) is pivotally secured to a pair of projections 48 of the base 30 plate 12 by means of a pivot pin 49, and provided at the other end with an aperture 50 within which shaft 26 is designed to rotate. Suitable means, for example a slotted bracket 51, may be provided to guide bar 46 in a vertical direction and prevent 35 lateral movement thereof.

To permit limited pivotal movement of upper shaft 26 relative to the lower shaft 16 and about bearing 27 so as to raise upper roller 29, the bearing surface 52 of bearing 27 is of arcuate shape 40 in cross-section, as shown particularly in Fig. 2.

A roller 53 designed to press lightly upon the inner surface of the crown 54 of the hat and to maintain the outer edge 16 of the brim 21 in contact with the wall 39 of the hub 34 of the 45 upper roller 29, is rotatably mounted on a bar 55 which, in turn, is slidably relative to the upper roller 29 and resiliently urged toward the same by a relatively weak spring 56. Pin and slot connections 57 prevent lateral movement of bar 50 55, and a handle 58 serves to manipulate the bar 55 and guide roller 53 for insertion of the brim and the lower part of the crown between the guide roller 53 and the upper roller 29. As shown by Fig. 2, bar 55 is preferably shaped and supported so as to produce the least friction against the base plate 12, and is so positioned that guide roller 53 impinges upon the crown 54 at a point substantially in line with the forward edge 53 of the upper roller 29, as shown particularly in 60 Fig. 1.

A stationary guide 60, shown in Figs. 1 and 5, consists of a hat support 61 and an arm 62 secured to the support at one end and having its 65 free end 63 spaced from the support. The opposed surfaces 64 and 65 of the arm 62 and support 61 substantially conform in shape to one another to accommodate and guide the hat brim 21 between rollers 19 and 29.

For heating the upper roller 29, a gas flame is projected from a nozzle 67 against the inner walls of the chamber 35. If it is desirable to heat the lower roller 19 also, a second nozzle similar to nozzle 67 may be provided to project a gas flame 70 75

against the walls of the chamber 37 in the lower roller 19.

It has been found desirable, according to the invention, to soften the felt of the brim by steaming the same continuously while the same is being acted upon by the rollers 19 and 29, in order to facilitate and improve the bead-forming and brim-finishing operation of the rollers. For this purpose, steam lines 68 and 69 are provided to project jets of steam through nozzles 70 and 71, preferably upon both the upper and lower sides of the brim 21 and shortly prior to the passage of the brim between the rollers. The amount of steam supplied may be adjusted by any suitable means, for example, either by making nozzles 70 and 71 of the adjustable type, by valves such as shown for example at 72, or by any other means.

In addition to or in place of nozzle 71, a jet of steam may also be projected upon the lower side of the brim 21 through a steam line 69' connected to a passage 69a within the stationary guide 60 which terminates into a nozzle passage 71', as shown in Fig. 5. By locating the mouth of the nozzle passage 71' at a point closely adjacent the upper end 65' of the guide surface 65, only the marginal portion of the brim 21 on which the bead 32 is to be formed, will be softened by the steam. Any suitable means (not shown) may be provided for regulating the amount of steam projected from the nozzle passage 71'.

Because the nap of the brim is depressed during the bead-forming operation by rollers 19 and 20, it may be desirable to raise the nap after the brim has passed through the rollers. For this purpose, a steam line 73 may be provided to project a jet of steam through a nozzle 74 at least upon the upper surface of the brim 21, and said jet may be regulated by a valve 75 in a similar manner as described above. Each of the steam jets projected through nozzles 70, 71, 71' or 74 can therefore be regulated independently of the others, and one may be shut off completely while the pressure of the other may be increased.

The novel method according to the present invention briefly consists of the continuous succession of steps of: softening or loosening the felt of the hat brim; continuously rotating the hat; applying rolling pressure moving in the same direction as the hat, at least upon one side of the brim and at a section thereof spaced inwardly from the outer edge of the brim; and gradually extending the rolling pressure from such intermediate section toward the outer edge of the brim so as to transplant or "flow" portions of the felt from the intermediate section to the outer edge of the brim to build up a bead thereon. In continuous succession with this method, the further steps may be added to shaping and pressing the bead, and then loosening the pressed portions of the brim and raising the nap thereon.

The operation of the apparatus according to the invention for carrying out this method is as follows:

The motor (not shown) is started to drive the main shaft 10 and thereby rotates shafts 16 and 26 and rollers 19 and 29 continuously and in opposite directions. Bar 46 is then pivoted by a foot treadle so as to pivot shaft 26 about bearing 27 and lift the upper roller 29 together with upper bearing block 42 against the action of springs 43. Concurrently with this operation, guide roller 53 is drawn manually toward the left as seen in Fig. 2 against the action of spring 56, and the brim 21 of a hat is inserted into the stationary guide 60 and then placed upon the lower roller 19. The foot treadle is thereupon

released whereby the heated upper roller 29 is urged by springs 43 against the upper surface of the brim 21, and at the same time guide roller 53 is released so as to bear lightly upon the inner surface of the crown 54 of the hat and maintain the outer edge 76 of the brim in contact with the wall 39 of the upper roller 29. The hat is then continuously rotated by the rotation of the rollers 19 and 29 in opposite directions and their action upon the brim 21. Steam is thereupon directed at least upon the upper surface of the brim to soften the felt.

In order to facilitate the formation of the bead 32 and to improve the final appearance and stability of the brim, the thickness of the latter prior to the bead-forming operation preferably increases toward the outer edge as shown in Fig. 4, while the space between the rollers gradually decreases toward the groove 31. By the gradual and continuous rolling and pressing action of the rollers upon both sides of the brim and the difference in the shape of the two rollers, the surface portions at least of the intermediate section 75 of the brim are gradually displaced and forced toward the outer edge 76 until the groove 31 in the upper roller has been filled out completely by such displaced felt and a bead 32 has been obtained. By varying the relative pressure of the rollers 19 and 29 upon the brim 21 by adjusting springs 43, brims and beaded edges of different hats may be given different solidity.

After continuously rotating the hat and rolling the brim for a certain length of time depending upon the particular kind of material worked upon, the guide roller is withdrawn from contact with the inner surface of the crown 54 and the foot pedal is again depressed so as to pivot bar 46 and lift the upper roller 29 from the finished brim 21. The completed hat is then removed from the lower roller and another hat inserted into the apparatus and operated upon in the same manner as previously described. Therefore, the brims of a large series of hats may be finished and provided with a beaded and tied edge in a continuous operation. Furthermore, the operation of the apparatus according to the invention does not require particular skill, and even an unskilled laborer may learn to operate the apparatus properly within a short time.

The hats finished with the present method and apparatus possess a brim of superior quality and appearance.

Inasmuch as by the application of rolling pressure upon the brim and the concurrent movement of the brim in the general direction of rotation and at the peripheral speed of the rollers, the friction upon the brim is practically avoided, the dull finish of the brim including its beaded edge is maintained and a shiny appearance of the brim usually obtained with the ironing methods known prior to the invention, is successfully avoided. The dull finish of the brim may be further improved as above described by steaming the brim and raising the nap thereof after it has passed through the rollers. Furthermore, since the beaded edge along the outer margin of the brim is formed of a single integral layer of material, as distinguished from a turned-over edge, it is completely safe against fraying or unravelling.

Although the invention has been described with particular reference to a hat with an upwardly curved brim, the apparatus can also be modified to bead and finish any other types of brims. In such event, it is merely necessary to replace

rollers 19 and 29 by rollers shaped according to the desired brim. Also, the beaded edge as produced according to the invention may be given any desired cross-sectional shape by providing a groove in the upper roller of a shape different from that shown in the drawings. Furthermore, by the same general method as described above, a bead may also be formed on the lower surface of the brim by providing a groove in the lower roller 19, and the bead may be built up at an intermediate portion of the brim rather than at the outer edge thereof.

Variations and modifications may be made within the scope of the invention and portions of the improvements may be used without others.

Having thus described the invention, what is claimed as new is:

1. A process of finishing hats comprising the steps of continuously rotating a hat in one direction and concurrently applying rolling pressure simultaneously upon both surfaces of the brim of the hat at a section spaced inwardly from the outer edge thereof; gradually shifting the pressure from the inner section of the brim toward the outer edge thereof to flow material of the inner section toward the outer edge to build up a bead on said edge; and ironing the bead.

2. An apparatus for forming a beaded edge on a hat brim, including a pair of rollers having opposed operating faces disposed peripherally thereof and adapted to receive a hat brim therebetween, one of said rollers having a peripheral groove therein; and portions on said operating faces converging relative to each other toward said groove to compress the section of the brim adjacent the groove and form a beaded edge on the brim and in said groove.

3. An apparatus for forming a beaded edge on a hat brim initially formed with an unbeaded edge, including a pair of rollers having opposed operating faces disposed peripherally thereof and adapted to receive a hat brim therebetween, one of said rollers having a bead receiving peripheral groove formed in the operating face thereof; portions on said operating faces, adjacent and at one side of said groove, in closer spaced relation than adjacent portions on said operating faces spaced from said side of the groove, for compressing a section of said brim and forming a bead on the adjacent section of the brim facing said groove; means for supporting a hat with the brim thereof between said operating faces; and means for rotating said rollers.

4. An apparatus for forming a beaded edge on a hat brim initially formed with an unbeaded edge, including a pair of rollers having opposed operating faces disposed peripherally thereof and adapted to receive a hat brim therebetween, one of said rollers having a bead receiving peripheral groove formed in the operating face thereof; means on one of said rollers for engaging the marginal edge of the brim and for locating the latter relative to said groove; means for supporting a hat with the brim thereof between said operating faces; and portions on said operating faces, adjacent and at one side of said groove, in closer spaced relation than adjacent portions on said operating faces spaced from said side of the groove, for compressing a section of said brim and forming a beaded edge on the brim and in said groove.

5. An apparatus for forming a beaded edge on a hat brim, including a pair of rollers having opposed operating faces disposed peripherally thereof and adapted to receive a hat brim there-

between, one of said rollers having a circumferential groove formed in the operating face thereof; a wall on one of said rollers, defining one side of said groove and engageable with the marginal edge of said brim for locating the latter relative to the groove; projecting means on said other roller cooperable with said wall, for arresting relative axial movement of said rollers in one direction; and portions at one side of said groove and on said respective operating faces, for pressing the section of the brim confined thereby and providing a bead on the marginal section of the brim facing said groove.

6. An apparatus for forming a beaded edge on a hat brim, including a roller member having an operating face disposed peripherally thereof and formed with a circumferential groove; an associated member having an opposed operating face, said operating faces being adapted to receive a hat brim therebetween and having portions converging relative to each other toward said groove; means for engaging the marginal edge of said brim and locating the latter relative to the groove; and means for rotating said roller to progressively compress a section of the brim between said converging portions and to provide a bead on the adjacent marginal section facing said groove.

7. An apparatus for forming a beaded edge on a hat brim, including a pair of rollers having opposed operating faces disposed peripherally thereof and adapted to receive a hat brim therebetween, one of said operating faces having a circumferential groove formed therein; means on one of said rollers for engaging the marginal edge of the brim and locating the same relative to said groove; portions on said opposed faces converging relative to each other toward said groove; means for engaging the inside of the hat crown and urging the brim toward said brim edge engaging means; and means for rotating said rollers to progressively compress a section of the brim between said converging portions and to provide a bead on the adjacent marginal section facing said groove.

8. An apparatus for forming a beaded edge on an initially unbeaded hat brim, including a pair of rollers having opposed operating faces disposed peripherally thereof and adapted to receive a hat brim therebetween, one of said rollers having a bead receiving peripheral groove therein, and said operating faces having opposed portions adjacent and at one side of said groove, in closer spaced relation than adjacent opposed portions spaced from said groove to compress the section of the brim at one side of the groove and form a bead on the section of the brim facing said groove; means for supporting a hat with the brim thereof between said operating faces; resilient means for urging at least one of said rollers toward the other; and means for rotating said rollers.

9. An apparatus for forming a beaded edge on a hat brim, including a pair of rollers having opposed operating faces disposed peripherally thereof and adapted to receive a hat brim therebetween, one of said rollers having a circumferential groove formed in the operating face thereof; means on one of said rollers, for engaging the marginal edge of said brim and locating the latter relative to the groove; portions at one side of said groove and on said respective operating faces, for compressing the section of the brim confined thereby and providing a bead on the marginal section of the brim facing said groove; means for supporting a hat with the brim thereof

between said operating faces; and normally stationary means for engaging the marginal edge of the brim and guiding the same to said rollers.

10. An apparatus for forming a beaded edge on a hat brim initially formed with an unbeaded edge, including a roller member, having an operating face disposed peripherally thereof and formed with a bead receiving circumferential groove therein; an associated member having an opposed operating face, said operating faces being adapted to receive a hat brim therebetween and having opposed portions adjacent and at one side of said groove, in closer spaced relation than adjacent opposed portions spaced from said groove 15 to compress the section of the brim at one side of the groove and to provide a bead on the mar-

ginal section facing the groove; and a plate having a surface extending toward and providing a substantial continuation of the operating face of one of said members, for supporting a hat with the brim between said rollers.

11. A process for finishing hats having a brim of felted material and initially formed with an unbeaded edge, including the steps of steaming the brim; and progressively compressing by means of rolling pressure a narrow strip around 10 said brim at a short fixed distance from the outer edge to a lesser thickness than before, to form a depressional groove in one face of the brim and to provide a beaded edge on said brim thicker than said compressed strip.

HERBERT H. WATSON, JR.
